J. OLSEN

PIN SPOTTER

Filed May 2, 1927

UNITED STATES PATENT OFFICE.

JOHN OLSEN, OF ROCK RAPIDS, IOWA.

PIN SPOTTER.

Application filed May 2, 1927. Serial No. 188,187.

The object of my invention is to provide a pin spotter of the kind used in bowling alleys of simple, durable and inexpensive construction.

5 A more particular purpose of the present invention is to provide such a pin spotter having certain novel features of construction and arrangement, whereby efficiency in the operation of the device is made certain and 10 easy.

Another object of my present invention is to provide a pin spotter having parts so constructed and arranged as to facilitate the convenience of installing the spotter in 15 the bowling alley.

With these and other objects in view, my invention consists in the construction, arrangement and combination of the various parts of my pin spotter, whereby the objects 20 contemplated are attained, as herinafter more fully set forth, pointed out in my claims, and illustrated in the accompanying drawings, in which:

Figure 1 is a plan view of a portion of a 25 bowling alley equipped with a pin spotter embodying my invention.

Figure 2 is a perspective view of a pin spotter embodying my invention.

Figure 3 is a detail, sectional view taken 30 on the line 3—3 of Figure 1.

Figure 4 is an enlarged, sectional view illustrating one of the centering fingers of the spotter in its environment when installed; and

35 Figure 5 is an enlarged, sectional view of a portion of the spotter, illustrating the detail structure of the fingers.

In bowling alleys, it is desirable to have some means for accurately spotting the pins.

40 Pin setters are generally used, but they do not always accurately set the pins exactly on the proper spots, and there is therefore the necessity for a spotter, which will simultaneously adjust all of the pins for accurately placing them.

In the drawings herewith, I have used the reference numeral 10 to indicate generally the floor of a bowling alley at the side of which is the ball race 12.

50 At the rear end of the alley floor 10, there is the lower cushioned floor 14 with the cushioned rear wall 16 and side walls 18.

It will be understood that at the rear end of the floor 10, there is a drop-off of several 55 inches.

It is my purpose to provide a pin spotter,

which can be installed below the rear end of the alley floor for projecting a plurality of fingers upwardly through the floor in the centers of the spots where the pins stand. 60 These fingers may be projected into the pins for properly spotting them.

It will be noted that the floor 10 is provided with spots 20 for placing the pins 22.

65 My improved pin spotter comprises a suitable supporting frame A having the rear transverse member 24, the side members 26 extended forwardly and toward each other, and the front cross member 28 as shown in Figure 2.

70 Arranged to cooperate with the frame A is a movable frame B triangular in shape and comprising angle bars 30 arranged with horizontal flanges and outer vertical flanges 30^a and 30^b.

75 At the corners of the frame B are yokes or the like 32, which are supported in any suitable way as for instance on the frame A for guiding the frame B in its up and down movement.

80 The frame B is provided with one transverse connecting frame member 34.

85 Mounted in the angle bars of the frame B and in the frame member 34 are suitable fingers 36, having tapered upper ends 36^a. These fingers are so mounted as to have a limited amount of play and to be readily detachable from above.

In the frame members of the frame B at proper places are holes 38. For each hole 90 38, there is provided a sleeve or socket 40 having in its upper portion a threaded hole 43 to receive the threaded end 36^b of the finger 36.

95 The hole 38 is large enough to loosely receive the socket 40 and allow considerable play thereof.

A small stirrup 42 is fixed to the under side of the flange 30^a of the frame B. The stirrup 42 has a rivet 42^a positioned to extend from one side thereof to the other and loosely projected through a hole 44 in the socket 40. The socket 40 rests on the bottom of the stirrup 42.

105 It will thus be seen that the socket 40 and the finger 36 mounted therein has some vertical play and some horizontal play in every direction as illustrated in Figure 5.

110 In the floor 10 at the center of each spot 20 is a hole 46 in which is mounted a bushing 48 to serve as a guide and wearing member for the finger 36.

The spot 20 may be of ebony, fiber or the like, and the upper end of the bushing 46 is flush with the top thereof, which has a hole 50 to receive the bushing 48.

5 Each pin 22 has in its bottom a countersink 52 with a beveled wall, as shown, and at the upper end or apex of the countersink, it has an upwardly projecting bore 54.

10 It will be seen that when the pins 22 are set on the spots 20, it is quite difficult to exactly center them on the spots.

Assuming that they have been set with ordinary accuracy, then when the frame B is pushed upwardly from below, the fingers 36 will first enter the countersinks 52 and then the bores 54 for accurately spotting the pins 22.

15 It will be understood that normally the frame B is lowered to position where the fingers 36 are wholly received in the floor in the position for instance illustrated in Figure 4.

20 I will now explain the mechanism for raising the frame B.

25 Mounted on the frame A between the side members 26 thereof, near the forward end of the frame A, is a cross member 56 on which is mounted a bracket 58. Mounted on the rear frame member 24 of the frame A is a bracket 60. A U-shaped lifting yoke 62 has its arms pivoted as at 64 to the bracket 60 and projecting forwardly therefrom. Fixed to the central part of the yoke 62 is an arm 66, which extends rearwardly and has a foot 30 pedal portion 68 and an upward extension 70. The arm 66 has the spaced ears 72.

Fore-and-aft angle bars 74 connected with the rear frame member of the frame B and with the cross frame member 34 in such position as to stand directly above the forwardly extending arms of the yoke 62.

40 Pivoted to the bracket 58 is a bell crank lever 76, having an upstanding pair of arms, to which is pivoted the forward end of a link 78. The link 78 has its rear end pivoted between the ears 72 of the arm 66.

45 The bell crank 76 has a forwardly projecting arm which normally stands below a cross bar 80 on the frame B.

50 The central portion of the link 78 is offset downwardly, so as to extend below the frame member 34 and the rear member of the frame B. The parts are thus so mounted that by depressing the foot pedal 68 or the extension 55 70, the forwardly extending arms 62^a of the yoke 62 will engage the member 74, and the forwardly extending arm of the bell crank 76 will engage the cross bar 80.

55 The frame B will thus be held level as it is raised and this will prevent any possible binding of the fingers 36 in the bushings 48 or spots 20.

60 The frame A may be blocked up by supports 82 from the sub-floor beneath the bowling alley floor 10 or may be hung in any

suitable way from the under surface of the bowling alley floor 10. The frame B will normally rest by reason of its weight on the frame A.

65 I will now explain with a little more fullness the installation and operation of my improved pin spotter and in connection with this explanation will call attention to some of the advantages of its construction.

70 The pin spotter is installed beneath the floor 10 of the bowling alley at the rear end thereof.

75 Where the pin spotter is installed at the time of the original building of the floor, the problem of installation is a rather simple 80 one. The frame A can be supported from below the floor 10 or shored up or otherwise supported from below in any suitable way to give it rigid mounting.

85 Where it is desirable to install the spotter under a floor that has been laid, a more difficult problem arises.

90 Frequently the installation must be made in a space of relatively little height. It is therefore desirable to be able to detach the fingers 36 during such installation.

95 I have therefore provided the form of device in which the fingers 36 may be unscrewed from the sockets 40. The two frames may be slid under the floor 10, and the frame A shored up, as shown in Figure 3, and then the fingers 36 may be inserted through the spot holes from above and 100 screwed into the sockets 40.

I can thus install my spotter in a narrower 100 space, than would be possible if it were not for the detachability of the fingers 36.

105 Another desirable feature arising from the detachability of the finger 36 arises from the fact that in case one of the fingers 36 should become broken accidentally, the portion remaining in the socket 40 may be taken out and a new finger 36 inserted from above, without removing the frames A and B from their installation under the floor 10.

110 It is not such a difficult proposition to make the fingers 36 detachable, but it is somewhat of a problem to make them detachable, and at the same time to permit them have that free play, which is highly 115 desirable in a device of this kind.

120 This free play I have provided for by the detachable threaded connection between the finger 36 and the socket 40 and by means of the loose play of the socket 40 in the hole 38 and on the rivet or arm 42^a.

125 Assuming that the device has been installed and is ready for use, it will be seen that the frame B ordinarily will rest on the frame A.

130 Assume then that the pins 22 are set on the spots 20 either by the pin boy or by a pin setter, then the foot pedal 68 may be depressed or the extension 70 may be engaged and depressed as by means of the

structure shown in my co-pending application, Serial No. 191,684 filed May 16, 1927, whereupon the arm 62^a and the bell crank 76 will lift the frame B, retaining it in 5 horizontal position, so that the fingers 36 will not bind, for raising the fingers 36 vertically.

The fingers will engage the beveled walls of the countersinks 52 in the case of any pins 10 22 not then exactly centered, sliding the pins 22 toward proper central position until the fingers 36 enter the portions 54 for accurately spotting the pins 22.

The frame B may then be permitted to 15 drop, and the pins 22 will be in exactly the right positions.

It will be seen that I have provided a pin spotter of very simple construction, which may be conveniently installed at the time the 20 bowling alley is built or afterwards.

The frame B has enough play for all practical purposes and yet is held in substantially horizontal position during its rising and lowering movement.

25 The fingers 36 are easily detachable from the sockets 40 so as to permit their replacement from above the floor 10 without taking out the frames A and B, and so as to permit the installation of the frames under a floor 30 that has already been laid, and the subsequent insertion of the fingers 36 from above. Ample play of the fingers 36 is permitted by reason of the structure by which they are mounted on the frame B. The bushings 48 35 protect the floor against wear and are used wherever it seems desirable to employ them.

It will be understood that changes may be made in the shape, material, construction and arrangement of the parts of my improved 40 pin spotter without departing from the real spirit and purpose of my invention, and it is my intention to cover by my claims any modified forms of structure or use of mechanical equivalents, which may be reasonably included within their scope.

I claim as my invention:

1. In a pin spotter, a frame, means for 45 supporting said frame for limited vertical movement, means for raising and lowering said frame, a plurality of socket members, a plurality of stirrup devices secured to said frame, said sockets being loosely mounted in said stirrup devices for limited vertical

and horizontal movement and a plurality of fingers fixed to said socket members. 55

2. In a pin spotter, a frame, yokes, means for raising and lowering said movable frame, a plurality of substantially upright fingers, a plurality of sockets mounted on said frame for limited vertical and horizontal movement, said fingers and sockets having co-operating parts for detachably connecting them together. 60

3. In a pin spotter, a frame, means for supporting said frame for limited vertical 65 movement, means for raising and lowering said frame in a horizontal plane, a plurality of upright fingers, a plurality of sockets, said frame having a plurality of holes for loosely receiving said sockets, said sockets 70 and fingers having coacting means for detachably connecting them together, and means for mounting the sockets on the frame for limited vertical movement.

4. In a pin spotter, a frame, means for 75 supporting said frame for limited vertical movement, means for raising and lowering said frame in a horizontal plane, a plurality of upright fingers, a plurality of sockets, said frame having a plurality of holes for loosely receiving said sockets, said sockets 80 and fingers having coacting means for detachably connecting them together, and means for mounting the sockets on the frame for limited horizontal movement. 85

5. In a pin spotter, a frame, means for supporting said frame for limited vertical movement, means for raising and lowering said frame in a horizontal plane, a plurality of upright fingers, a plurality of sockets, said 90 frame having a plurality of holes for loosely receiving said sockets, said sockets and fingers having coacting means for detachably connecting them together, and means for mounting the sockets on the frame for limited 95 vertical and horizontal movement.

6. In combination with a pin spotter frame, a finger supporting device comprising a stirrup on the frame, a rivet carried thereby, an opening in the frame adjacent said 100 yoke, a socket member having an opening larger than said rivet and positioned thereon whereby it extends loosely through said opening in the frame and a pin secured to said socket member.

JOHN OLSEN.
